Adelaide

UNITED STATES PATENT OFFICE.

AUGUSTE DESGOFFE, OF ODESSA, RUSSIA.

GOVERNOR FOR ENGINES.

SPECIFICATION forming part of Letters Patent No. 544,061, dated August 6, 1895.

Application filed November 10, 1891. Serial No. 411,525. (No model.) Patented in Belgium January 8, 1890, No. 89,115; in France January 23, 1890, No. 203,322, and in Italy May 20, 1890, No. 27,538/81.

To all whom it may concern:

Be it known that I, AUGUSTE DESGOFFE, a citizen of France, residing in Odessa, in the Empire of Russia, have invented certain new and useful Improvements in Governors for Engines, (for which Letters Patent have been granted in France, dated January 23, 1890, No. 203,322; in Belgium, dated January 8, 1890, No. 89,115, and in Italy, dated May 20, 1890, No. 27,538/81,) of which the following is a description.

My present invention relates to governors; and it consists of certain novel parts and combinations of parts, which will be specifically pointed out in the claims concluding this specification.

The following is a description of the governor shown in the accompanying drawing; but it will be understood that my invention is not limited to the precise devices and combination of devices here illustrated and described, as various modifications in the structure may be made without departing from the spirit of my invention and without exceeding the scope of the concluding claims.

The drawing herewith filed illustrates a longitudinal section through a governor containing my present invention.

I will now describe the structure indicated in said drawing, which is one of the forms in which I at present prefer to embody my invention, while in the claims I will indicate the novel features of my invention and will specify the subject-matter covered by these Letters Patent.

2 is a base or bed-piece on which are set standards 3 3.

4 is a shaft attached to any revolving part of an engine or other contrivance to which 40 the regulator is applied.

5 is a piston keyed to the shaft 4.

6 is a cylindrical case provided with head-pieces 7 and 8. The bottom head-piece 8 is provided with four perforated ears, two of 45 which 9 9 are shown slipping over the standards 3 3 (only two of the four being shown) and free to rise and fall on said standards. Each of the standards 3 is surrounded by a spiral spring 10, which at one end bears upon 50 the top of the ears 9 and at the other end

against a collar 11, surrounding the standard 3, held in place by pin 12.

The head-piece 7 is provided with a pin having a screw-thread 13 on an enlarged section, forming a plug in the said head-piece 55 and securing thereto an eye 14.

15 is a set-screw or plug stopping a hole in the cover 7. The cover 7 is provided with a flange, forming a ledge all around its top, to which a cylindrical envelope 16 is attached 60 at one end. At the other end it is attached to a ledge on the bottom head-plate.

The space 17 is formed between the outer walls of the case 6 and the inner walls of the envelope 16. This forms an annular reservoir 65 open to the air at 18.

The shaft 4 is bored at its upper end to receive the pin 19, provided with longitudinal groove 23, which, in connection with ears 9 and standards 3, form a guide for the case 6 70 as it rises and falls, as hereinafter described.

22 is a stuffing-bag surrounding the shaft 4 to prevent the escape of the fluid contained in the cylinder at the point where the shaft enters the case.

In certain applications for Letters Patent I have illustrated and described what I call the "antispire" system, in which opposing surfaces, each provided with threads inclined in opposite directions, form, in general terms, the characteristic feature. To these specifications reference is here made for a fuller description of the general principles and features of structures operating on this principle.

The piston 5 is provided with spiral threads 20 20, inclined in one direction, and the case 6 is likewise provided with spiral threads 21 21, inclined in the opposite direction, so that where the inclined surfaces are face to face 90 these threads cross each other at a given angle, which angle, generally speaking, I prefer should be seventeen degrees forty minutes. As I have said before, the piston 5 is keyed to the revolving shaft 4, which is connected to any suitable moving part of an engine or other device to which it is attached, and, according to principles fully explained in my said applications, it is obvious that if water, oil, or any other suitable fluid have free access 95 100

to the lower part of the case 6 the revolution of this piston will propel it against the upper head 7 of the cylinder 6 with a force proportional to the velocity at which the piston revolves.

The operation of the device above described may be thus stated: The lower part of the cylinder-chamber 6 is filled with water, as is also the reservoir 17. This reservoir is open 10 to the air at 18. Hence, the revolution of the piston 5, propelling the water against the cover 7, causes those parts of the structure to which the cover is attached to rise against the force of gravity and against the force of the 15 springs 10 10. The elevation which it will reach is determined by the pressure of the water against the head, which in turn is determined by the speed at which the piston revolves. The eye 14 is connected, by suitable 20 levers or other contrivances, with the valve controlling the admission of steam, gas, water, or whatever may be the substance operating the device, so that as the case rises the motive power is more or less diminished and as 25 it falls the motive power is more or less increased. In this way perfect regulation of the speed of the device may be obtained.

It will be observed that in this regulator the use of all flexible or elastic parts is avoided, 30 and that a non-elastic medium, such as water, glycerine, &c., is employed, so that every change of speed of the engine operates the governor, which instantly acts upon the valve controlled thereby. This governor is extremely sensitive and responds instantly to 35 the slightest variation of speed of the engine controlled thereby. Indeed, its sensitiveness is practically unlimited, owing to the fact that the oppositely-inclined grooves operate 40 in a positive manner upon the inelastic fluid under pressure. This regulator may be placed horizontally or in any inclined position. If inclined, preferably the annular reservoir containing the fluid should be in communication 45 with a supplemental reservoir to supply it with such fluid.

The antispire grooves, their form, number, and dimensions, may vary according to the requirements of the device and they may be 50 of any required inclination, although in general I prefer to give them, both on the piston and on the case, an inclination of seventeen degrees forty minutes. However, the opposite grooves need not have the same inclination. As is more fully pointed out in my said 55 pending application, the essential relation between the grooves on the opposing surfaces is that they must form angles with each other, and it is not therefore necessary that the 60 grooves of both surfaces have the same inclination.

In the foregoing specification I have described a few of the modifications which may be employed in the practice of my invention, 65 but I have not endeavored to describe all the modifications which may be suggested, as the

object of this specification is to instruct others skilled in the art to practice my invention in forms which are at present preferred, and to understand its nature; and it will therefore be understood that the mention by me of a few modifications is not intended to exclude others not referred to, but which are within the spirit and scope of my invention.

Certain details, illustrated and herein described, are not essential to the several features of my invention, broadly considered. All this will be pointed out in the concluding claims, as the omission in a given claim of reference to an element, or the omission of 80 reference to the particular features of the elements contained, will be understood to be a formal declaration of the fact that the omitted elements or features are not essential to the operation of the invention covered by said 85 claim.

Having thus described the preferred structure involving my present invention, what I claim, and desire to secure by Letters Patent, is—

1. In a regulator, the combination of a plurality of opposing surfaces, each provided with continuous threads, the threads of the opposing surfaces being inclined so as to cross each other, a reservoir containing fluid acted 95 upon by said threads, a movable part controlled by said fluid, a motor or equivalent device, by which said piston is caused to revolve, and suitable connections between said reservoir and admission valve of said motor, 100 or equivalent device, to control the admission of the acting fluid.

2. In a regulator, the combination of a plurality of opposing cylindrical surfaces, each provided with continuous threads, the threads 105 on the opposing surfaces being inclined so as to cross each other, one of said cylinders being free to move longitudinally and the other being adapted to revolve, a reservoir containing fluid acted upon by said threads having a 110 movable part controlled by said fluid, a motor or equivalent device, by which one of the elements is caused to revolve, and suitable connections between said movable part and the admission valve of said motor, or equivalent 115 device, to control the admission of the acting fluid.

3. In a regulator, the combination of an inclined cylindrical surface provided with continuous threads, a piston provided with continuous threads inclined so as to cross the threads on the case, a motor, or equivalent device by which said piston is caused to revolve, a reservoir containing fluid acted upon by said threads, said case being adapted to 120 move longitudinally, suitable connection between said case and the admission valve of 125 said motor, or equivalent device, to control the admission of the acting fluid.

4. In a regulator, the combination of a case 130 provided with continuous threads, a piston provided with continuous threads, the threads

- on the piston and case being inclined so as to cross each other, an annular reservoir surrounding said case, said case being adapted to move longitudinally, a motor or equivalent device, by which said piston is caused to revolve and suitable connections between said case and the admission valve of said motor, or equivalent device, to control the admission of the acting fluid.
- 5 5. In a regulator, the combination of a case provided with continuous threads, a piston provided with continuous threads, the threads on the piston and case being inclined so as to cross each other, said case being adapted to move longitudinally, guides for the case and means for transmitting the movements of the case to the admission valve of the motor, or analogous structure, to be regulated.
- 10 6. In a regulator the combination of a case provided with continuous threads, a piston provided with continuous threads, the threads on the piston and case being inclined so as to cross each other, a motor or analogous structure, to be regulated, a shaft connecting a moving part of the motor and said piston, said shaft being bored at its upper end and a pin projecting from the upper cover of the case

into the bored end of the piston, a reservoir containing fluid acted upon by said threads, a movable part controlled by said fluid and 30 suitable connections between said case and the admission valve of said motor, or analogous structure, to control the admission of the acting fluid.

7. In a regulator the combination of a case 35 provided with continuous threads, a piston provided with continuous threads, the threads on the piston and case being inclined to cross each other said case being controlled by fluid acted upon by said threads adapted to have 40 a longitudinal motion and said piston being adapted to have a rotary motion, guides for controlling the movements of the case, a spring for resisting the propelling action of the piston against said case, a motor or equivalent 45 device, by which said piston is caused to revolve, and suitable connections between said case and the admission valve of said motor, or equivalent device, to control the admission of the acting fluid.

AUGUSTE DESGOFFE.
